CHICKEN BROODER AND FINISHING
BATTERY

Albert E. Kinkaid, Bearden, Tenn.

Application October 29, 1932, Serial No. 640,265

1 Claim. (Cl. 119—34)

The present invention relates to a chicken brooder and finishing battery, and primarily aims to provide a brooder particularly adapted to raise chickens for market purposes.

5 It is also a primary object of the invention to provide a brooder including a plurality of heated and ventilated compartments intended to receive and house chicks differing in degree of maturity, and having means for controlling separately the heat and ventilation within the individual compartments, thus permitting to regulate the temperature and draught for the proper raising of the chicks of a certain age in a particular compartment.

10 Another important object of the invention resides in the provision of a battery brooder unit comprising a plurality of individual compartments having means for conducting under control fresh outside air directly thereto and to each of its compartments.

15 It is also among the desired features of the invention to provide a device of the character mentioned constructed of knock-down sheet metal parts formed for interlocking engagement, thus 20 eliminating the use of fastening elements and allowing for quickly assembled and dismantling; the metallic structure of the device further permitting the same to be easily and readily cleaned and kept sanitary by use of water, steam spray, or flame torch, without injuring the parts thereof.

25 Other important objects and advantages of the invention will be in part obvious and in part pointed out hereinafter.

30 In order that the invention and its mode of operation may be readily understood by those persons skilled in the art, I have in the accompanying drawings and in the detailed description based thereupon, set out a possible embodiment 35 of the same.

40 In these drawings:

Figure 1 is a front elevation of the battery unit;

Figure 2 is a side elevation thereof partly in section;

45 Figure 3 is a vertical section taken on the line 3—3 of Figure 2 in the direction of the arrow points but having the drawers removed therefrom;

Figure 4 is a vertical longitudinal sectional view 50 of one form of a removable drawer adapted to be used in connection with the brooder;

55 Figure 5 is a detail transverse section through a portion of the brooder frame having a drawer of the type as disclosed in Figure 4 arranged thereupon and this drawer being shown in sec-

tion and such section being taken on the line 5—5 of Figure 4 in the direction of the arrow points;

Figure 6 is a detail longitudinal section through one of the secondary heat conducting pipes for 5 illustrating the construction of the dampers employed;

Figure 7 is a detail elevation of one of the stanchions having one of the channel bars connected thereto and said channel bar being shown 10 in section, and

Figure 8 is a slightly enlarged detail sectional view of one of the humidifying devices.

Having more particular reference to the drawings wherein like characters of reference will designate corresponding parts throughout, the construction of my improved brooder consists of a cabinet having arranged therein a plurality of superposed tiers and removably supported upon each tier is a drawer or compartment for housing the chicks. The forward end of the cabinet is of an open construction whereas the rear end thereof is properly enclosed in order that heat at controlled temperatures may circulate through the closed portion of the cabinet about the rear 25 ends of each of said drawers or compartments. The framework of the cabinet consists of two pairs of stanchions, each being herein indicated by the numeral 1. One pair of stanchions is arranged at the forward end of the cabinet, whereas the other pair of stanchions are arranged at the rear end thereof and are indicated in Figure 3 of the drawings by dotted lines. The forward pair of stanchions have their lower ends connected together by means of a cross bar 3a and these 35 forward stanchions are connected to the rear housing of the cabinet by means of the bars 3b. A cover 38 is provided for the cabinet and rests upon the upper ends of these stanchions. This cover is provided with depending side bars 3c 40 which provide braces for the upper ends of the forward pair of stanchions.

Upon the upper flange 4 of each of the spaced channels 3, is supported a drawer 5. Each drawer is constructed of sheet metal and is provided with 45 a rear section 6 of less height than the main section of the drawer, for the purpose to be later specified. The front and sides of the main section of the drawer 5 are formed with a plurality of elongated apertures 7, whereby access 50 may be had to the feed and water troughs 7' suspended outwardly of the drawer. Each of the water troughs may be provided with hooks 7a which engage the drawers by extending through the openings 7 thereof and are further provided 55

- with depending arms 7b which contact with the outer face of the drawers so as to provide means for detachably connecting the troughs to the drawers as is better illustrated in Figure 4 of the drawings. In each type of drawer as shown in Figures 4 and 5, slots 11 are formed in the walls thereof through which may extend suitable fastening elements 10 carried by the plates 8. These plates are for the purpose of covering the openings 7 and have formed therein smaller openings or slots 9 in order that the drawers may accommodate smaller chicks. The bottom of the drawer is constituted by a removable screen comprising a mitered metal frame 12 clampingly engaging the screening 13. The screen frame 12 is supported upon the drawer 5 by engagement within channel guides 14 formed with the end panels of the drawer, and rests on flanges 15 bent inwardly from the side panels of said drawer.
- 20 The reduced rear section 6 of the drawer supports upon its top a screen 16 resting upon flanges 17, and receives a perforated metal screen 18 adapted to protect the chicks from the walls of said section 6 of the drawer.
- 25 Pivoted transversely of the drawer near the reduced rear section 6 thereof, is a plate valve 19 having a counterweight extension 20. A chain 21 guided by means of rollers or pulleys 22, and passing through a tube 23 affixed to the upper portion of the drawer, is connected to the counterweighted extension 20 of the plate valve 19 and projects at the front of said drawer as at 24, whereby said valve plate may be manually operated.
- 30 The drawer assembly may be bodily withdrawn from or placed in position within the unit, and, in its movement, it is guided by means of guides 25 carried by the supporting channels 3.
- Underneath the drawer 5 is positioned a drop pan 26 slidably supported upon the lower flange 27 of the channel 3.
- Arranged about the back of the unit frame and portions of its sides, that is, inclosing the reduced rear section of the drawer 5 when in position in said frame, are parallel inner and outer sheet metal walls defining chambers therebetween.
- 35 The chamber defined by the back inner wall 28 and outer wall 29 forms a ventilation shaft 30, the lower end of which registers with a conduit 31 placing said shaft in communication with the outside air, whereby fresh air discharges directly in said shaft. The back inner wall 28 is provided with rectangular openings 32 extending substantially throughout the entire width of the wall, and disposed immediately above the screened top of the reduced section 6 of the drawer 5 when in position. At said openings, the inner wall 28 is formed with hood extensions 33 projecting over said section of the drawer. In this manner, fresh outside air is directly circulated to each individual drawer or compartment wherein the chicks are to be raised. A valve 34 is mounted at each opening in order to control the ventilation in each compartment. The valves 34 are independently controllable by means of chains 35 or the like connected to a corresponding valve. Valves 36 likewise supplied with operating chains 37, are also provided at the top and bottom of the shaft 30 for control of the ventilating air circulation therein. The chains 35 and 37 are passed over the top cover 38 of the unit and are accessible at the front thereof as indicated at 39.
- 40 The chambers defined by the side inner walls

40 and outer walls 41, provide a pair of diametrically opposed ducts 42 protecting a contiguous pipe 43 or the like which runs transversely in and out of each of the compartments hereinbefore described. The portions of the pipe 43 extending throughout the compartments, are disposed immediately below the hood extensions 33 formed with the back inner wall 28. The lower end of the pipe 43 projects outwardly of one of the ducts 42, as indicated at 44, and is connected to a suitable heater 45 of any well known type. The upper end 46 of the pipe 43 projects through the top 38 of the unit and forms an escaping vent. Those portions of the pipe 43 positioned within the compartments are supplied with a pair of secondary pipes 47 communicating therewith, in order that the circulating heat medium may be distributed to advantage throughout the compartments.

As will clearly appear upon reference to Figure 20 3 of the drawings, the main pipe 43 and secondary pipes 47 are slightly slanted in the upward direction, and this is for the purpose of facilitating the normal circulation of the heat transmitting medium. Each secondary pipe 47 is provided at its lower end portion with a damper 48 for controlling the circulation of said medium. A damper 49 similar in construction to that of the damper 48 is provided adjacent the vent portion 46 of the main pipe 43. The dampers 48 and 49 are counterweighted as at 50 (Fig. 6) to normally return to their closed position. These dampers 48 and 49 are each provided with an operating lever 51.

That the proper degree of humidity may be supplied to the brooder, a water pan 52 is supported adjacent the heat medium circulating pipes 43 and 47 within each compartment. As illustrated in Figure 8, the water is automatically supplied to the pans 52 through a float operated 40 valve 53 interposed in a common supply pipe 54 leading from a reservoir 55 arranged upon the unit top cover 38 (Figs. 1 and 2). Any surplus water which may be discharged into the pans 52 is taken off through a branched overflow pipe 45 56 opening in a suitable tank 57 at the lower portion of the unit.

From the foregoing, it will be appreciated that I have provided a brooder battery unit construction which is most advantageous for raising and finishing chickens.

In use, the newly hatched chicks are preferably placed in the uppermost drawer where they remain for two or three weeks. This group is then divided and placed into the second and third 55 drawers or compartments, where they are fattened until the eighth or ninth week. During this time, the chickens are observed and the larger fowls are removed from the two latter compartments to the lowermost drawer where 60 they are finished for the market.

The particular features of the invention which permit the independent control of the heat, ventilation and humidity in each individual compartment, afford an advantage of the greatest 65 importance, since they allow the positive regulation within each compartment of the temperature and ventilation most suitable for the breeding of the chickens of different degree of maturity raised in the battery unit.

It will be understood that through the construction of my improved device, fresh outside air is discharged directly into each compartment. In this manner, it is assured that no foul air will be breathed by the chicks raised in the various 75

compartments of the unit. Fresh air is taken directly from the outside, with the flow or velocity of current being controlled by dampers at the inlet to the fresh air conduit. The ventilator 5 at the top of the fresh air shaft regulates the amount of fresh air therein. The fresh air ventilators to each compartment can be regulated to control the flow and amount of fresh air into each of said compartments, the air being suitably heated from the heat medium circulating 10 pipe directly outside of the ventilator. After the warm fresh air currents have served their purpose, they pass out through the front of the unit by natural gravitation of cool-warm air circulation.

15 Due to the all metallic construction of the unit, the same may be kept clean and sanitary by use of water, steam spray or flame torch, without injury to the parts. Also, due to the knock-down 20 construction of the unit, it will be appreciated that the same may be quickly and readily assembled or taken apart without requiring special tools or particular skill. Likewise, the knock-down construction facilitates the handling and 25 shipping, thus imparting to the invention, a meritorious commercial value in supplying the trade.

Manifestly, the construction shown and 30 described is capable of considerable modification and such modifications as come within the scope of my claim I consider within the spirit of my invention.

35 I claim:—

A brooder of the character described, comprising a plurality of compartments adapted to be mounted within a brooder house; an air circulat-

ing shaft common to all of said compartments and disposed at the rear portion thereof; means establishing communication between said shaft and each individual compartment; conduit means leading from outside the brooder house and opening into said shaft whereby to discharge fresh air from outside the brooder house directly into each of the compartments and create a natural circulation therein; means in each compartment defining a partially closed chamber therein, said 10 chamber communicating with the air circulating shaft through said communication establishing means and with the remainder of the compartment for admitting fresh air into the latter; a heat medium circulating main conduit running 15 continuously in and out from one compartment to the other, that portion of the heat medium circulating main conduit in each compartment being disposed within the partially closed chamber therein whereby to heat the air before its 20 admission into the remainder of the compartment; heat medium circulating secondary conduits communicating with that portion of the main conduit positioned in said chamber within each compartment; valves controlling the communication between said portion of the main conduit and secondary conduits; valve means arranged at the point of communication of said chamber with the air circulating shaft for varying the amount of fresh air thereinto to be heated; and other valve means positioned adjacent the point of communication between the chamber and the remainder of the compartment for controlling the amount of heated air discharged 25 within the respective compartments.

30 35 ALBERT E. KINKAID.
